US0D1047679S

(12) **United States Design Patent** (10) **Patent No.:** **US D1,047,679 S**
(45) **Date of Patent:** **** Oct. 22, 2024**

(54) **BUNGEE CORD ADJUSTABLE PLASTIC PART**

(71) Applicant: **Shenzhen Xingmeng Technology Co., Ltd.**, Guangdong (CN)

(72) Inventor: **Junhong Tian**, Guangdong (CN)

(73) Assignee: **Shenzhen Xingmeng Technology Co., Ltd.**, Shenzhen (CN)

(**) Term: **15 Years**

(21) Appl. No.: **29/956,431**

(22) Filed: **Aug. 7, 2024**

(51) LOC (14) Cl. **08-08**

(52) U.S. Cl.

USPC **D8/383; D21/839**

(58) **Field of Classification Search**

USPC D8/383, 356; D21/839

CPC F16G 11/14; E04H 15/32

(57) **CLAIM**

The ornamental design for a bungee cord adjustable plastic part as shown and described.

DESCRIPTION

FIG. 1 is a perspective view of a bungee cord adjustable plastic part showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is bottom plan view thereof.

The broken lines depict portions of the bungee cord adjustable plastic part and form no part of the claimed design.

1 Claim, 8 Drawing Sheets
